FINGER RING WITH SPRING GUARD

Moe Manne, New York, N. Y.

Application February 20, 1951, Serial No. 211,853

4 Claims. (Cl. 63—17)

1

This invention relates to finger rings, and more particularly to a means by which a finger ring will more readily fit fingers of various diameters and which will also prevent the ring from turning or rotating on the finger.

The difficulty encountered in securing a finger ring of proper fit is well known and while efforts have, in the past, been made to secure a more accurate and comfortable fit of a finger ring, the optimum sought has not been attained. The objection found in many prior devices applied to finger rings to secure a more satisfactory fit of the ring has primarily been that such device was applied to the ring as a separate attachment or accessory which was often rendered visible when the ring was worn. Other devices were of fragile construction, and repeated removal and replacement of the ring from the finger soon resulted in damage to the attachment resulting in it being discarded. Some of the devices often caused a pressure on the finger which made the ring uncomfortable to wear.

It is an object of the present invention to provide a device which will enable a ring to be worn snugly but with comfort; which will permit the ring to freely slide over the knuckle joint, yet will position and hold the ring at the base of the finger with sufficient firmness and friction to prevent rotative movement of the ring on the finger. It is another object of the invention to provide a device of this character which may be readily attached to many rings of known construction; which will be invisible when worn and which will be effective to enable the ring to be comfortably worn on fingers of various diameters.

More particularly, the invention contemplates the provision of a ring having a recess in the under side of its top and one or more coil springs attached at the under side of the top in registration with the recess, which springs will be stretched or tensioned along the line of the recess and can be expanded to a necessary extent thereinto when the ring is being placed on the finger and particularly when the same is being forced over the knuckle joint.

In the accompanying drawing, where in an illustrative embodiment of the invention is disclosed,

Fig. 1 is a side elevation of a ring constructed in accordance with the invention;

Fig. 2 is a similar view of the ring, with the upper portion or top of the ring being shown in section;

Fig. 3 is a sectional view taken on the line 3—3 of Fig. 1, looking in the direction of the arrows; and

2

Fig. 4 is a side elevation of a modified structure.

Referring to the drawing, 1 indicates the shank portion of a ring which is generally of conventional construction and is provided with the conventional top 2 having the also conventional elongated recess 3 in its under side. At the opposite ends of the recess 3 are provided fixed anchorages or hooks 6 and 7 to which are attached the opposite ends of a coil spring composed of two sections 4 and 8 respectively. At its center, the coil spring extends over a fixed cross bar or pin 5 which extends across or bridges the recess 3, said bar 5 being located substantially at the center of the ring. The position of this transversely-extending bar or pin 5 is such as to divide the spring, and which may be continuous or of one piece, into the two sections 4 and 8 which are thus disposed angularly to one another as clearly shown in Figs. 1 and 2. It will be apparent that, if desired, each of the sections 4 and 8 may be separate, said separate sections in such case, having one end anchored at the bar 5 and the other at one of the hooks 6 or 7. The spring composed of the parts 4, 8, is held under slight tension and when the finger is inserted through the finger opening in the ring, it will be obvious that the spring sections 4 and 8 can be expanded to readily permit the passage of the finger and especially to permit the ring to readily pass over the knuckle joint.

As the spring sections 4 and 8 are expanded as above described, they may readily be extended into the recess 3 to such an extent as may be required to permit the finger to readily pass. When the ring has reached its position at the base of the finger, the springs will apply sufficient pressure on the finger to hold the ring snugly in its proper position on the finger yet without applying abnormal or uncomfortable pressure. The pressure alone applied by the springs will probably be sufficient to prevent the ring from turning or rotating on the finger. However it is to be noted that the convolutions of the springs engaging the surface of the finger will provide a frictional contact with the surface of the finger which will hold the ring from turning, yet without applying sufficient friction on the finger to cause discomfort to the wearer of the ring.

50 The construction of the device is such that it may be readily applied to almost any ring having a recessed top, since the modifications required to a ring to enable the spring or springs to be fitted thereon consist merely of formation or production of the anchorage hooks 6 and 7 and the

central cross bar 5, and these elements can be readily applied to almost any ring.

In the embodiment of the invention disclosed in Fig. 4, the central cross bar 5 is dispensed with and a single spring 9 extends across the ring and transverse to the axis thereof. Said spring 9 has one end anchored at the hook 6 and its other end attached at the hook 7. The operation of this structure is substantially similar to that shown in Figs. 1 to 3 inclusive.

In the two embodiments shown, the spring or springs are expanded by the insertion of the finger through the ring, the spring or springs extending into the recess 3 to the extent required by finger pressure, particularly at the knuckle, and when the finger passes the knuckle, the spring or springs will contract sufficiently to hold the ring firmly on the finger and prevent its rotative movement as above described.

While I have herein shown and described two 20 embodiments of the invention, it is obvious that the same is not to be restricted thereto but is broad enough to cover all structures coming within the scope of the annexed claims.

What I claim is:

1. A finger ring having a top provided with a recess in the under side thereof, a coil spring located below said recess and extending across a portion of the opening through the ring and having its opposite ends anchored at the opposite ends of the recess, a support extending across the recess at a substantially central point therein, said spring being extended over and supported by said support to thereby divide said spring into two sections arranged angularly with respect to one another, said sections being capable of being expanded to at least partly enter said recess when a finger is inserted through the opening of said ring.

2. A finger ring having a top provided with a recess in its under side, a cross bar extending across said recess at a substantially central point therein, coil spring sections supported at one end by said cross bar, anchorages at said opposite ends of the recess for respectively receiving the opposite ends of the coil spring sections,

said spring sections extending across a portion of the opening through the ring and transversely to the axis of the ring and longitudinally of said recess and being capable of fitting at least partly into said recess when a finger is inserted through the ring.

3. A finger ring having a hollow top formed with a recess in its under side, a tensioned coil spring in said ring extending across a portion 10 of the opening through said ring and transverse to the axis of said ring below said recess so that said spring can be expanded at least partly into said recess when a finger is inserted through said ring, a support arranged in said recess on the under side of said ring, said spring being tensioned by being passed over said support, and anchorages at the opposite ends of said recess for receiving the opposite ends of said coil spring.

4. The combination with a finger ring having its inner periphery provided with an elongated recess, of an adjustable attachment positioning said ring at the base of a finger and frictionally holding said ring against rotative and longitudinal displacement relative to said finger, said attachment comprising an elongated coil spring arranged within the opening of said ring adjacent said recess and in position to be at least partially accommodated in said recess during and upon insertion of said ring on said finger, a support carried within said recess intermediate the ends thereof, said coil spring being passed over and tensioned by said support, and means on the inner periphery of said ring for anchoring said coil spring on said ring adjacent to the opposite ends of said recess.

MOE MANNE.
